PACKAGE

Walter Mitchell, Jr., Scarsdale, N. Y.

Application August 7, 1941, Serial No. 405,853

17 Claims.

(Cl. 206—56)

This invention relates to containers and/or packages, and more particularly to a container and/or package exteriorly shaped to conform to the contour of portions of the human body so that it may be conveniently carried in a trouser hip pocket or side pocket of a coat.

More specifically, the invention relates to a package containing a plurality of disposable paper tissues preferably folded and rolled into generally cylindrical form.

One of the principal objects of the invention is to provide a container for packaging a number of disposable paper tissues, such as paper handkerchiefs of the "Kleenex" type, but individually rolled into compact cylindrical form.

Another object of the invention is to provide convenient and sanitary means for carrying a number of disposable tissues upon the person.

Another object of the invention is to provide a package which may be permanently sealed at its edges and which is provided with suitable means for facilitating the withdrawal of the contents of the package without breaking the sealed portions.

Still another object of the invention is to provide a thin concavo-convex container which may be cheaply made from a single sheet of pasteboard.

A further object of the invention is to provide a container for elongated substantially cylindrical objects, such as disposable tissues rolled into substantially cylindrical form, cigarettes, stick candy, etc., the package being so shaped in cross-section that it can be conveniently and comfortably carried about the person without bulging the pockets.

A further object of the invention is to provide a container having an opening or window in the front wall thereof through which the contents of the container can be removed without mutilating the container.

A further object of the invention is to provide a windowed container for elongated articles, the window opening being so shaped as to permit removal of said objects irrespective of whether said objects are arranged longitudinally or transversely in said container.

A still further object of the invention is to provide a package comprising a container having a plurality of disposable tissues therein which may be conveniently carried in a pocket, or purse, and the whole economically manufactured and sold at a low cost.

Other and further objects of the invention will be apparent from the following description taken

in conjunction with the accompanying drawings, in which:

Fig. 1 is a perspective view of one embodiment of the invention in which the edges of the package are closed or sealed and the front wall of the package is provided with a suitable, normally sealed window opening through which the contents may be readily removed;

Fig. 2 is a rear view of the package shown in Fig. 1 with portions broken away to facilitate illustration of the structure thereof.

Fig. 3 is an end elevation of the package shown in Fig. 1;

Fig. 4 is a longitudinal sectional view taken on the line 4—4 of Fig. 1;

Fig. 5 is a transverse sectional view taken on the line 5—5 of Fig. 1;

Fig. 6 is a view of a blank, on a reduced scale, from which a package such as shown in Fig. 1 may be made;

Fig. 7 is a front elevational view of another form of windowed package; and

Fig. 8 is a fragmentary transverse sectional view of still another form of container falling within the purview of the present invention.

Referring now to Figs. 1 to 5, inclusive, the package is generally indicated by the letter P and comprises a container 1 having a front wall 2 provided with a generally T-shaped window 3 or opening 3. The window 3 is preferably normally closed by a sheet of cellophane or transparent paper 4, although it will be apparent that said opening need not be closed in certain instances, as when the package contains wrapped stick candy. A rear wall 5 is connected to the front wall 2 by a side or end wall 6. The front and rear walls 2 and 5, respectively, have projecting flaps 7 and 8 which are adapted to be overlapped and to be adhesively secured together, as is best shown in Fig. 5. The side portion 6 carries tabs 10 at its opposite ends and the flap 7 carries similar tabs 11 at its opposite ends.

Referring to Fig. 6, the blank from which the container 1 is made is generally indicated by 1*. This blank is designed to be punched out of a sheet of substantially inelastic pasteboard. The portion corresponding to the rear wall 5 of the container 1 is preferably scored on an arc at its upper and lower ends, as indicated by the dotted lines at 12 and 13 to facilitate bending of said rear wall to provide a bowed or curved upper end wall 14 terminating in a flange 15 and an oppositely bowed or curved lower end wall 16 terminating in a flange 17. The blank 1* is preferably further scored along the dotted vertical lines 18

to provide for easy folding of said blank to form the front and rear walls 2 and 5, respectively, one side wall 6, and the other side wall consisting of the overlapped flaps 7 and 8. The blank 1^a is still further scored horizontally, as indicated by the dotted lines 19, to provide for ready bending of the tabs 10 and 11. The blank 1^a obviously may be scored at the time that it is cut. The sheet 4 for closing the opening 3 is shown in dot-and-dash lines.

It will be particularly noted from Fig. 6 that the scoring at 12 and 13 is formed on an arc so that when the end portions 14 and 16 are bent along the score lines 12 to a position at substantially right angles to the vertical plane of the rear wall 5, said rear wall will automatically be caused to bow outwardly or assume a concavo-convex shape. Similarly, upon bending the rear wall along the score lines 13, to provide the vertical flanges 15 and 17 at substantially right angles to the plane of the bowed ends 14 and 16, the general curvature of the flanges 15 and 17 will substantially coincide with that of the rear wall 5. Thus, it will be apparent that, upon bending the rear wall 5 upon the score lines 12 and 13, said rear wall automatically takes a bowed shape without any distortion of the end walls 14 and 16 and the flanges 15 and 17. Bending of the blank 1^a along the lines 18 and 19 will complete the major folding operations on the container.

After scoring, but prior to bending or folding, the rear wall portion 5 is provided with adhesive, as shown at 20 and 21, whereby the tabs 10 and 11 can be adhesively secured to the end walls 14 and 16 by the adhesive 20 and the flanges 15 and 17 can be secured to the inner surface of the front wall 2 by the adhesive 21. The flap 7 is provided with adhesive 22 for securing it to the flap 8. The tabs 10 and 11 serve to substantially reinforce the ends of the container structure and the flanges 15 and 17 automatically cause the front wall 2 to conform to the curvature of the rear wall 5 and maintain said front wall in substantially parallel relationship with said rear wall. It will be understood, of course, that the sheet 4 closing the opening 3 (when employed) is adhesively secured to the blank 1^a prior to folding the same into container form.

As has been previously indicated herein, the container 1 is particularly well adapted to carry a plurality of generally cylindrical objects, such as disposable paper tissues 23 suitably folded to provide a convenient length and then rolled into substantially cylindrical form. The package P may be of any suitable size, depending upon the number of rolled tissues to be packed therein. These tissues are preferably inserted as a group through one end of the container between the front and rear walls 2 and 5, after the flaps 7 and 8 have been secured together but before the ends 14 and 16 of the package have been bent and sealed. Of course, this procedure of assembling the package is not critical and departure therefrom may be indulged in without departing from the scope of the invention.

The tissues 23 may be disposed either longitudinally or transversely in the container 1. As one illustration of packaging, Figs. 4 and 5 show the tissues 23 disposed transversely or horizontally, the tissues being inherently yieldable to conform to the curvature of the container, as shown in Fig. 5. It will be apparent that the container 1 is better adapted to carry said tissues when disposed in a longitudinal or vertical posi-

tion because then no distortion of the cylindrical form of the tissues is necessary. However, the window 3 is so formed as to permit ready removal of the tissues 23 regardless of the arrangement of said tissues, as will be explained herein-after.

It will be obvious that the tissues 23 can be individually removed through the window opening 3 by tearing or severing the sheet 4 which preferably closes the opening. With reference to Fig. 1, and assuming that the tissues 23 are disposed transversely, those tissues which are in alignment with the stem portion 3^a of the T-shaped opening 3 can easily be removed by pulling the same through the opening at this point by the fingers. Those tissues which are disposed to one side of the stem portion 3^a can easily be removed by shifting the same toward said stem and then withdrawing the same in the manner just described. It will also be obvious that, should the tissues 23 be disposed vertically in the package shown in Fig. 1, they may be easily removed individually by pulling the same through the head portion 3^b of said T-shaped opening. Those tissues which do not happen to be in alignment with the head portion 3^b can readily be shifted toward the left side of the container 1 by projecting a finger through the stem portion 3^a of the T to move the tissues into alignment with said head portion of the T. The T-shaped opening 3 obviously can be positioned horizontally instead of vertically and the tissues 23 removed from the container 1 with equal facility.

As will be apparent from Fig. 5, the total length of the opening 3 is less than the length of the rolled tissue 23 so that said tissue is retained in the container until it is forcibly pulled through the opening. Once the tissue has been removed, it can readily be unrolled and unfolded, if desired, for use.

While the package P has been described in detail in connection with roller paper tissues, it is to be understood that the container 1 is not restricted to such use.

Fig. 7 shows another form of the invention in which the package is similar in construction to that previously described herein except that the front wall 2 of the package is provided with a generally cross-shaped opening 24 instead of a T-shaped opening. The container here shown also illustrates vertical or longitudinal disposition of a plurality of cylindrical objects 23^a within the container so that the same may be conveniently removed through the vertical portion 24^a of the cross-shaped opening. As is here shown, the objects 23^a may be of slightly shorter length than the length of vertical portion 24^a, so as to permit ready removal thereof without danger of breaking the objects if they happen to be of a fragile character. Those objects not aligned with the portion 24^a of the opening 24 can be readily shifted into alignment by inserting a finger through the horizontal portion 24^b of said opening. A sheet 25, which may have any suitable configuration, prevents the objects 23^a from inadvertently coming out of the container. If the objects are slightly longer than the opening 24^a, they may be shifted bodily upwardly until the lower end thereof can be raised through said opening. Once the end is raised, the object can then be freely withdrawn.

Fig. 8 illustrates another form of the invention wherein the front wall 2^a of the container can be made solid or windowed, as desired. In order

to provide for removal of the contents of a package having a solid front wall 2^a, the side edge of said wall is provided with a wall portion 26 and a flap or tongue 27 extending therefrom which is adapted to be inserted into an opening 28 formed at one side of the package. The tongue 27 is shown in full lines in its closed position and is shown in dot-and-dash lines in a position that it may assume when the package has been opened to allow withdrawal of its contents.

The flap or tongue structure 27 also is advantageous when used in a container having a window (not shown) in the wall 2^a, in that it eliminates the flap 8 of the blank 1^a and provides for sealing the side wall of the container by adhesively securing the tongue 27 to the inner surface of the rear wall 5^a, in a manner readily understood. The tongue 27 provides the further advantage that the container may be completed, that is, have the end walls bent and adhesively secured in place, prior to the insertion of the goods into the container through the side opening 28. The final packaging operation would then consist of closing the opening 28 by sealing the tongue 27 in place against the inner surface of the rear wall 5^a.

It will be understood that various modifications and changes may be made in the shape of the openings in the front of the container, and that various other changes may be made in the manner of sealing and filling the container without departing from the spirit of the invention or the scope of the annexed claims.

I claim:

1. A container comprising: a single sheet of material folded to provide front and rear walls; side walls; and oppositely bowed end walls interconnecting said front and rear walls, said front wall being convex and said rear wall being concave with said front and rear walls lying substantially parallel with each other, said front wall having an opening through which the contents of said container may be withdrawn.

2. A container as defined in claim 1, in which the opening includes portions extending substantially at right angles to each other.

3. A container as defined in claim 1, in which the opening is substantially T-shaped, is formed in said convex wall and has the stem of the T disposed in the direction of curvature of said wall.

4. A container as defined in claim 1, in which the opening is formed in said convex front wall and is substantially cross-shaped.

5. A container comprising: a single sheet of material folded to provide front and rear walls; side walls; and end walls, said front and rear walls being bowed transversely and lying substantially parallel with each other, said side walls being straight and substantially parallel with each other, and said end walls being bowed in opposite directions and connecting said front wall with said rear wall.

6. A container as defined in claim 5, in which the front wall is provided with an opening through which the contents of the container may be withdrawn.

7. A container comprising: paper material folded to provide front and rear walls; straight side walls; and end walls carried by said rear wall interconnecting said front and rear walls, said front and rear walls being curved transversely and lying substantially parallel with each other, one of the side walls of said container

being hinged to said front wall along a fold line and having an extension in the form of a tongue providing means whereby access to the contents of said container may be attained from the side of the container.

8. A container comprising: a single sheet of material folded to provide front and rear walls; side walls; and end walls interconnecting said front and rear walls, said front and rear walls being bowed transversely and lying substantially parallel with each other, said end walls being bowed in opposite directions, and one of the side walls of said container being hinged to said front wall along a fold line and having an extension in the form of a tongue providing means whereby access to the contents of said container may be attained from the side of said container.

9. A container comprising: bowed front and rear walls; a side wall connecting adjacent side edges of said front and rear walls at one side of the container; flaps projecting from said front and rear walls at the other side edges thereof, said flaps being secured together in overlapping relation to form a second side wall of said container; and bowed end walls each having a bowed flange secured to said bowed front wall.

10. A container comprising: bowed front and rear walls; side walls connecting adjacent side edges of said front and rear walls; tabs extending from said side walls; and bowed end walls adhesively secured to said tabs, said bowed end walls each having a bowed flange adhesively secured to said bowed front wall.

11. A container comprising: front and rear walls; a side wall connecting adjacent side edges of said front and rear walls at one side of the container; flaps projecting from said front and rear walls at the other side edges thereof, said flaps being secured together in overlapping relation to form a second side wall of said container, said first-mentioned side wall and one of said flaps being provided with tabs; and curved end walls secured to said tabs, said curved end walls each having a curved flange secured to said front wall.

12. A concavo-convex container for rolled tissue, cigarettes, stick candy and the like comprising: a single sheet of material folded to provide bowed front and rear walls; side walls connecting adjacent side edges of said front and rear walls at the opposite sides of the container; oppositely bowed end walls carried by said rear wall, each of said bowed end walls having a bowed flange projecting outwardly therefrom and secured to the inner face of said bowed front wall, said bowed front wall having an opening therein through which the contents of the container may be removed; and means for closing said opening.

13. A package adapted to be carried about the person comprising: a one-piece cardboard container having curved parallel front and rear walls, side walls and opposite bowed end walls; a plurality of disposable tissues rolled into cylindrical form arranged side by side between said walls, one of said curved walls having an opening including portions arranged at substantially right angles to each other and through which opening said tissues may be individually removed.

14. A container comprising: a single sheet of material folded to provide substantially parallel bowed front and rear walls having straight sides and curved ends; side walls connecting adjacent side edges of said front and rear walls; and bowed end walls interconnecting adjacent curved

ends of said front and rear walls, said front wall having an opening providing access to the interior of said container.

15. A package comprising: a container having substantially parallel bowed front and rear walls having straight sides and curved ends, one of said walls having an opening through which the contents of said container can be removed; side walls connecting adjacent side edges of said front and rear walls; bowed end walls interconnecting adjacent curved ends of said front and rear walls; and a plurality of rolled tissues in said container removable through said opening, said opening having a length less than the length of the rolled tissue so that said tissue must be flexed during removal thereof from said container through said opening.

16. A package comprising: a container having substantially parallel bowed front and rear walls having straight sides and curved ends; side walls connecting adjacent side edges of said front and

5 rear walls; oppositely bowed end walls interconnecting adjacent curved ends of said front and rear walls; and a plurality of generally cylindrical yieldable objects disposed side by side in said container, one of said substantially parallel walls having an opening through which said objects can be withdrawn one at a time.

10 17. A package comprising: a container having substantially parallel bowed front and rear walls having straight sides and curved ends; side walls connecting adjacent side edges of said front and rear walls; oppositely bowed end walls interconnecting adjacent curved ends of said front and rear walls; a plurality of generally cylindrical yieldable objects disposed side by side in said container, one of said substantially parallel walls having an opening through which said objects can be withdrawn one at a time; and a frangible sheet secured to the inner face of said last-
20 mentioned wall and initially closing said opening.

WALTER MITCHELL, JR.
